J. F. ALLARD.
TYPEWRITING MACHINE.
APPLICATION FILED FEB. 13, 1918.

1,421,134.

Patented June 27, 1922.

FIG. 1.

UNITED STATES PATENT OFFICE.

J FRANK ALLARD, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

1,421,134.

Specification of Letters Patent. Patented June 27, 1922.

Application filed February 13, 1918. Serial No. 216,903.

To all whom it may concern:

Be it known that I, J FRANK ALLARD, a citizen of the United States, residing in Brooklyn Borough, in the county of Kings, 5 city and State of New York, have invented certain new and useful Improvements in Typewriting Machines, of which the following is a specification.

This invention relates to tabulating mechanism, in which provision is made for mechanically setting the column-stops to effective positions in a variety of groupings so that when changing from one class of work or printed form to another, a corresponding 15 change in the column-stops may be effected by simply adjusting a single part. A machine of this general character is illustrated in the patent to McLaughlin, No. 941,166.

In said patent, the column-stops form the 20 forward ends of blades or carriers which extend rearwardly and which carry lugs for engagement by an assortment of spurs, which are carried upon a revoluble shaft. By turning the shaft to different set positions, different groups of spurs may be 25 brought into use, and hence different column-stops may be mechanically selected; those stops which are no longer to be used being returned automatically to positions of disuse.

Owing to the construction of the column-stop blades or carriers, which extend rearwardly a considerable distance at the back of the machine, it is found that it is impracticable to use the McLaughlin mechanism in machines where other necessary devices are placed at the back of the typewriting machine in proximity to the carriage, as, for example, adding attachments, such as are used in the well-known Underwood- 40 Hanson combined typewriting and adding machine. An object of the invention, therefore, is to simplify and improve the column-stop mechanism, especially with a view to making the mechanical selecting devices 45 more compact, and also with a view to arranging them in such position that the use of other mechanisms at the back of the typewriter carriage is not precluded.

Instead of sliding the column-stops, I 50 pivot the same, and these pivoted stops extend in a row along the back of the carriage and close thereto. The stops may extend rearwardly from their pivots and may be very short, thus making a compact struc-

ture. They are normally in elevated positions, but any one may be swung to such a position that it can be reached by any of the decimal-tabulator stops which are usually arranged at the back of the machine and are liftable by individual keys. For compactness, the spur-carrying shaft, which controls the positions of the column-stops, may extend along the machine back of the carriage and above the column-stops, and the spurs upon said shaft may engage arms 60 which extend up from the column-stops. Hence, upon rotating the shaft, predetermined arms are pressed back and their stops are depressed to working positions. For convenience in setting the shaft, it may be 65 connected by any suitable means, as, for example, a chain and sprockets to a finger-piece arranged upon the carriage nearer the front of the machine; and an index and scale may be provided to guide the operator 70 in setting the same. In place of arranging four set positions, as in said McLaughlin patent, I have illustrated, for convenience, a shaft having only two set positions, this being intended to represent a shaft having 75 any desired number of set positions.

Other features and advantages will hereinafter appear.

In the accompanying drawings,

Figure 1 represents a plan of a carriage 85 and other portions of an Underwood typewriting machine, embodying the present improvements.

Figure 2 is a part-sectional side elevation 90 of the machine.

Figure 3 is a side elevation of part of Figure 2, showing the stops ineffective.

The Underwood typewriting machine herein illustrated has a non-shifting carriage and is provided with the usual decimal-tabulator keys 10, which are arranged upon the forward ends of levers 11, which are adapted to elevate individual decimal-stop-rods 12 mounted at the rear of the machine; each stop-rod being capable of operating through 95 a universal bar 13 to pull down a link 14, which, by means of a lever 15, will elevate a letter-feeding rack 16 carried upon the typewriter carriage 21, to release said rack from the control of the usual pinion 17 and escarpment wheel 18, so that the carriage may run along until arrested by means of the engagement of the decimal-stop 19 at the top 100 105

of a rod 12 with the succeeding set column-stop 20, which is provided upon said carriage. As usual in said Underwood machine, said carriage-escapement wheel 18 is controlled by dogs 22, which are operated by a universal bar 23, the latter being operable by any of the type-bars 24, as they swing towards the platen 25 which is mounted upon the carriage 21, aforesaid.

10 The column-stops 20 are shown pivoted upon a rod 26, which is fixed upon the back of the carriage, the stops extending rearwardly from the rod and each one having a spring 27 which keeps it in elevated position of disuse. These stops may work in a rack-guide or comb 28, which may form part of a bar 29 secured to the rear of the typewriter carriage by arms 29^a extending rearwardly therefrom. At its rear end, the 15 bar 29 contains said springs 27, which may be helical compression springs arranged in seats 30 carried in the bar 29. The rod 26, which carries the column-stops, may be arranged close to the rack 28, and, for convenience in arranging the column-stops thereon, may be detachably held in brackets 26^a, secured to the arms 29^a by screws 31.

For setting the column-stops, they are provided each with an upwardly-extending arm 32 adapted to be engaged each by its corresponding spur 33, the latter carried upon the revoluble shaft 34, and constructed so as to be settable at letter-space or other intervals, and operating as set forth in said patent.

When any spur 33 engages the corresponding upstanding arm 32 to rock the same backwardly, it thereby depresses the column-stop from its ineffective position, as 40 at Figure 3, to its effective position, as at Figure 2. As many arms 32 will be depressed as are engaged by cams or spurs 33 along the shaft 34, which spurs operate upon the principle set forth in said patent. The 45 spurs 33 at Figure 2 lock the arms 32 in abnormal positions, because they impinge thereon at dead center, but upon a succeeding quarter revolution of the shaft 34 the arms 32 will be released from the spurs, and the 50 springs 27 will return the column-stops 20; a new set of arms 32 being engaged by the remaining spurs 33 upon the further quarter rotation of the spur-shaft 34, thereby a new set of column-stops 20 being depressed to 55 working positions.

A finger-piece 35 may be journaled upon the carriage near the front of the machine and connected by sprockets 36, 37 and a chain 38 to the spur-shaft 34; and the finger-piece 60 may be connected to a notched detent wheel 39 controlled by a spring-pressed detent 40 also mounted upon the typewriter carriage; there being advantageously twice as many notches 41 as there are effective positions of the spur-shaft 34. For convenience

there may be provided at any suitable place, such as the detent wheel 39, a scale having numbers thereon, one for each effective position of said spur-shaft. The scale indication to be read may be shown by a pointer 42 beside the scale. The scale herein shown may comprise the letters "B", to indicate a setting of the stops for billing, and "I" to indicate a setting for inventory. The extra notches on the notched wheel are used to hold the spur-shaft in idle positions between its effective positions, in which idle positions all the setting arms are ineffective and all of the stops are retracted.

70 Since the machine herein illustrated has a non-shiftable platen, the shaft 34 may be journaled in brackets 43 and 44 screwed to the platen frame, the latter bracket also including an enlarged portion 45 forming a bearing for the sprocket 36. If the platen frame is shiftable, the mounting of the shaft 34 and some other parts may be suitably modified.

75 It will be noted that each operating arm or spur 33 comprises a hub 46 by which it is mounted on the shaft 34, and that each hub may comprise one or more of the spurs 33. The column-stops may be spaced at letter-space intervals, in which case there is a complete array of stops on the carriage, 90 and the stops, which are to be made effective, may be selected by merely positioning the spurs along the shaft 34 by their hubs. The column-stops 20 are prevented from being thrown out of the comb 28 by the springs 100 27, because their arms 32 will strike against either the hubs of the spurs 33 or against the shaft 34 itself before the stops rise clear of the comb 28.

75 Variations may be resorted to within the scope of the invention, and portions of the improvements may be used without others.

Having thus described my invention, I claim:

1. In a typewriting machine, the combination with a traveling carriage, of a vertically slidable stop, a plurality of column-stops pivoted on said carriage in advance of said vertically slidable stop, each of said column-stops having a rearwardly extending arm to co-operate with said slidable stop, and an upwardly extending arm, devices, one for each column-stop normally holding the same out of position to co-operate with said vertically slidable stop when in operative 110 position, a shaft adjacent said column-stops and above the pivots thereof, and cam members on said shaft adapted to operatively position said column-stops through co-operation with the upright arms thereof.

115 2. In a typewriting machine, the combination with a traveling carriage, of a rod carried on said carriage at its rear, a series of column-stops pivoted on said rod having rearwardly extending stop arms and rear-

wardly and upwardly extending operating arms, a setting shaft mounted above said rod, a counter-stop movable to a position to be engaged by an operatively positioned 5 column-stop, cams mounted on said shaft for actuating said operating arms and consequently said stop arms, a finger-piece mounted on said carriage in advance of said setting shaft, and a chain-and-sprocket connection between said shaft and said finger-piece.

3. In a typewriting machine, the combination with a traveling carriage and a shaft thereupon, of a plurality of column-stops 15 rotatable upon said shaft, a spring for each stop, normally holding it in inoperative position, a co-operating counter-stop adapted to be projected to arrest the carriage by any column-stop which stands in operative position, 20 a shaft extending along said column-stops, a plurality of members, comprising spurs, settable along said last-named shaft to be rotated thereby to be selectively effective to rotate said column-stops to operative 25 position, an arm on each column-stop forming a cam by which a spur may be effective thereon, certain of said spurs being effective on certain of said column-stops in one position of rotation of said spur-shaft, and 30 others effective in another position of rotation of said spur-shaft, a finger-piece, mounted on said carriage in advance of said spur-shaft, and a connection from said finger-piece to said spur-shaft for rotating it 35 to different positions for adjustment.

4. In a typewriting machine, the combination with a traveling carriage, of a rod thereon, a series of column-stops pivoted upon said rod, a counter-stop adapted to arrest the carriage by intercepting the operative column-stops, a spring for each column-stop, normally holding it in inoperative position, a shaft upon said carriage, a comb adapted to hold said column-stops against 40 sliding upon said rod, extensions of said column-stops adapted to strike said shaft to prevent the stops from being thrown clear of the comb, and spurs upon said shaft adapted to strike cam surfaces upon said 45 extensions to selectively throw the column-stops to operative position upon the rotation of said shaft.

5. In a typewriting machine, the combination with a traveling carriage, of a rod 55 thereon, a series of column-stops pivoted upon said rod, a counter-stop adapted to arrest the carriage by intercepting the operative column-stops, a spring for each column-stop normally holding it in 60 operative position, a shaft upon said carriage, a comb adapted to hold said column-stops against sliding upon said rod, extensions of said column-stops adapted to strike said shaft to prevent the stops from being 65 thrown clear of the comb, and adjustably

settable spurs, positioned longitudinally of and around said shaft, adapted to strike cam surfaces upon said extensions to selectively throw the column-stops to operative position upon the rotation of said shaft. 70

6. In a typewriting machine, the combination with a traveling carriage and a rod at the rear of said carriage, of column-stops journaled upon said rod, a counter-stop adapted to arrest the carriage by engagement with any operatively positioned 75 column-stop, a comb adapted to hold said column-stops against sliding, a spring for each column-stop adapted to hold it normally elevated in the comb in inoperative 80 position, a shaft adjacent said stops, arms on said stops extending near said shaft, and spurs secured upon said shaft to be rotated thereby to selectively strike said arms to make the column-stops effective. 85

7. In a typewriter, in combination, a carriage, and tabulating mechanism therefor, comprising a series of settable column-stops mounted along the rear of said carriage, a rotatable stop-setting device extending along 90 said stops and capable of effecting a plurality of different settings of stops of said series at a plurality of successive partial rotations, a rotatable manipulator for said setting device, said manipulator being 95 located forwardly thereof on said carriage and geared thereto, so that the parts of said mechanism located at the rear of said carriage may be operated to effect settings by means of said forwardly-located manipulator, a detent device to hold said setting device in its various stop-setting positions as 100 well as in its neutral positions, and indicating means comprising a scale and an index, one of said elements being mounted on said manipulator, and the other fixed in indexing relation thereto to designate the setting relation between said stops and their setting device. 105

8. A tabulating mechanism for a typewriter carriage comprising a plurality of column-stops pivoted at the rear of the carriage, a shaft adjacent said stops, arms mounted on said shaft to be selectively effective on said stops to control the effectiveness thereof, a counter-stop to co-operate with said column-stops, a finger-piece on said carriage in advance of said shaft, for rotating said shaft to vary the effectiveness of said arms, operative connections between 110 said finger-piece and said shaft, and indicating means, including a scale adjacent said finger-piece, to indicate how the arms are effective. 115

9. A tabulating mechanism for a typewriter carriage comprising a plurality of stops pivoted at the rear of the carriage, a shaft adjacent said stops, arms positioned on said shaft to be selectively effective on said stops to control their effectiveness, 120 125

means including a finger-piece in advance of said shaft for rotating said shaft to vary the effectiveness of said arms, means, including a scale adjacent said finger-piece, to 5 indicate how the arms are effective, and a device for holding said shaft in its various effective positions and also for holding the same in an ineffective position.

10. In a typewriter, in combination, a carriage, and tabulating mechanism therefor, comprising a series of settable column-stops mounted along the rear of said carriage, a stop-setting device extending along said stops and capable of effecting a setting 15 of a plurality of the same at a single operation, and a manipulator for said setting device, said manipulator being mechanically connected thereto and located forwardly thereof on said carriage, so that the parts 20 of said mechanism located at the rear of said carriage may be operated to effect set-

tings of said stops by means of said forwardly-located manipulator.

11. In a typewriter, in combination, a carriage, and tabulating mechanism therefor, 25 comprising a series of settable column-stops mounted along the rear of said carriage, a rotatable stop-setting device extending along said stops and capable of effecting a setting of a plurality of the same at a single 30 operation, and a rotatable manipulator for said setting device, said manipulator being geared thereto and located forwardly thereof on said carriage, so that the parts of said mechanism located at the rear of said carriage may be operated to effect settings 35 of said stops by means of said forwardly-located manipulator.

J FRANK ALLARD.
